RAILWAY COUPLER MOUNTING

James C. Travilla, Jr., Swarthmore, Grenville E. Jones, Lansdowne, and Robert E. Stein, Chester, Pa., assignors to General Steel Castings Corporation, Granite City, Ill., a corporation of Delaware

Application August 29, 1946, Serial No. 693,604

8 Claims. (Cl. 213—61)

1

The invention relates to supports for railway vehicle couplers and, more particularly, to the supporting of so-called "tight-lock" couplers which in use, have the inter-engaging heads of the couplers on adjacent cars secured together so that the two couplers move as a unit and not relative to each other as do ordinary couplers.

It will be understood that the adjacent ends of coupled vehicles have relative vertical movement because of the different spring action in their respective trucks. Also the adjacent vehicle ends may have relative movement transversely of their longitudinal axes because of play between their respective truck bolsters, frames, journal boxes and wheel and axle assemblies due, largely, to track inequalities and to successive stretches of curved and tangent tracks. Another relative movement of the adjacent vehicle ends occurs when one vehicle tilts or rotates about a longitudinal axis in one direction and the adjacent vehicle tilts or rotates about a corresponding axis in the opposite direction or to a less degree in the same direction.

The object of the present invention is to accommodate the above-mentioned relative movements when tight-lock couplers are utilized.

In the accompanying drawings, illustrating a selected embodiment of this invention:

Figure 1 is a horizontal section through the forward central part of a locomotive framing and pilot and is taken approximately on the line 1—1 of Figure 2 and shows a coupler with associated draft gear.

Figure 2 is a vertical longitudinal section of the same structure taken approximately on the line 2—2 of Figure 1; a portion of an adjacent coupler being also indicated.

Figures 3 and 4 are vertical transverse detail sections taken on the corresponding section lines of Figure 2.

Figure 5 is an isometric view of some of the parts sectioned in Figures 2 and 4.

The front end 1 of the locomotive framing mounts a pilot 2 recessed at 3 to receive a counterbalanced drop coupler structure 4, including a head 5 and a rigid shank 6. The locomotive framing includes sills 7 for mounting a draft gear 8 including a yoke 9. The coupler shank 6 and draft yoke 9 are connected by a link 10 bifurcated vertically at its forward end to receive the coupler and bifurcated horizontally at its rear end to be received in pockets in the draft yoke. The link is provided with a horizontal pivot 11 to the coupler shank and a vertical pivot 12 to the yoke 9.

2

The forward portion of coupler shank 6 is slidably supported by a bar 13 extending transversely of the locomotive and yieldingly supported through springs 14. The springs are seated on brackets 15 on upright webs 16 of the pilot. The springs are provided with inverted U-shaped caps 31, the depending legs of which extend alongside vertical portions of brackets 15. Bolts 32 extend through brackets 15 and the depending legs of caps 31, the brackets are slotted to permit restricted downward movement of the caps when the spring is compressed but to limit the upward movement of the spring caps and bar 13, thereby providing for easy application and removal of the bar.

Yoke 9 rests on a support 17 secured to spaced draft sills 7.

Link 10 connecting the coupler and draft gear is supported by a sliding universal joint structure comprising a block 18 connected by a pin 19, disposed longitudinally of the link and coupler, two depending ears 20 on the link, the block being slidable along a rod 21 disposed transversely of the links and coupler structure with its ends received in seats 22 slidable longitudinally of the locomotive along guides 30 on the pilot at opposite sides of the coupler.

Coupler 4 may be shifted from the functioning position shown in full lines in Figure 2 to the inactive position shown in broken lines by the removal of bar 13. This is executed by turning the locking key 23 at the right hand end of the bar (Figure 3) to horizontal position and withdrawing the bar by grasping its handle 24 at the left hand end of the bar. The coupler may then swing on pivot 11 so that the coupler head no longer projects forward of the pilot. The bar 13 may then be replaced in the pilot in a position above the coupler shank 6 to retain the coupler in lowered position.

With the coupler in operative position, as shown in full lines in Figure 2, coupler 4, link 10 and draft yoke 9 may move as a unit longitudinally of the locomotive to accommodate draft and buffering forces, the parts sliding on supports 13, 30 and 17, respectively. Coupler 4 and link 10 may swing as a unit horizontally about pivot 12 between the positions corresponding to those shown in full lines and broken lines in Figure 1, the forward portion of the coupler shank sliding on bar 13, and block 18 under link 10 sliding on rod 21 and the latter, with its slides 22, shifting on guides 30 as may be necessary to accommodate the movement of block 18 with link 10 radially about pivot 12.

Coupler 4, link 10 and yoke 9 may tilt or rotate, as a unit about the axis of pin 18, in which event shank 6 will tilt about one of its lower corners resting on bar 13 and yoke 9 will tilt about one of its lower corners resting on support 17 (see the broken line positions of these parts in Figure 4). This tilting movement of elements 4, 10 and 9 is facilitated by the fact that the axis of pin 18 and the yoke-engaging surface of support 17 are in substantially the same horizontal plane and by the fact that bar 18 may incline from the horizontal or may be depressed bodily by downward thrust from the coupler shank and the yielding of one or both of springs 14.

Variations in the relative heights of the adjacent couplers may be accommodated by inclination of the coupler shank about pivot 11 or by the inclination of the shank and connecting link 10 about pivot 18, without requiring movement between the inter-engaged couplers.

Hence it will appear that the interlocked couplers on adjacent vehicles may move as a unit irrespective of relative movements of the two vehicle structures on which they are mounted and such relative movements may be longitudinally, vertically or horizontally radially of the vehicles or angularly about a longitudinal axis.

The details of the above-described structure may be varied from those shown without departing from the spirit of the invention and the exclusive use of those modifications coming within the scope of the claims is contemplated.

What is claimed is:

1. Mounting for a railway vehicle draft gear and coupler structure comprising an elongated member extending transversely of the vehicle, and a universal joint device having a portion arranged to be pivotally secured to said structure and a portion slidably along said member.

2. In a support for a railway vehicle draft gear and coupler structure, a member having an aperture for a pivot pin adapted to be seated in the structure, and having an aperture for an elongated support, the axes of said apertures extending in transverse directions.

3. Mounting for a railway vehicle draft gear and coupler structure comprising a block having an aperture arranged to accommodate a pivot pin extending horizontally longitudinally of the structure, and having an aperture extending horizontally in a transverse direction, a supporting rod slidably received in the latter-mentioned aperture.

4. Mounting for a railway vehicle draft gear and coupler structure comprising guides on the

5 vehicle spaced transversely of the vehicle and extending longitudinally of the vehicle, seats slidably lengthwise of said guides, an elongated rod extending between and mounted in said seats, a block pivotally and slidably mounted upon said rod, and a bearing providing for pivoting of said structure on said block about an axis extending longitudinally of the vehicle.

5. Mounting for a railway vehicle draft gear and coupler structure comprising guides on the vehicle spaced apart transversely of the vehicle and extending longitudinally of the vehicle, seats slidably lengthwise of said guides, an elongated rod extending between and mounted in said seats, a block pivotally and slidably mounted upon said rod, a pin extending through said block transversely of said rod and structure-carrying elements pivotally assembled with said pin.

6. Mounting for a railway vehicle draft gear

20 and coupler structure comprising a bar extending transversely of the vehicle, yielding supports for the ends of said bar, a rod extending transversely of the vehicle and non-yieldingly supported on the vehicle and spaced longitudinally of the vehicle from said bar, a block slidably and pivotally mounted on said rod, a pin extending transversely of said rod and journaled in said block, and coupler structure-carrying elements journaled on said pin.

30 7. In a railway vehicle coupling structure, a coupler head and shank, a vertically yielding carrier near the forward end of the structure, said structure being slidable horizontally on said carrier, and means spaced rearwardly of the coupler from said carrier and supporting said structure for tilting action about axes extending longitudinally and transversely of said structure, said means providing for movement of the adjacent portion of said structure transversely of its axis.

40 8. In a railway vehicle coupling structure, a coupler head and shank, a link for connecting the coupler to a draft gear, a pin disposed lengthwise of the coupler and link, a member pivotally assembled with the link by said pin, an element supporting said member and extending transversely of the coupling structure and pivotally assembled with said member, bearings slidably supporting the ends of said element, and a carrier spaced from said element longitudinally of the coupling structure and yieldingly supporting said structure.
